UNITED STATES PATENT OFFICE.

LOUIS A. SCHMIDT, OF BROOKLYN, NEW YORK.

VENTILATING HEAD-SUPPORT OR PILLOW.

SPECIFICATION forming part of Letters Patent No. 364,377, dated June 7, 1867.

Application filed March 12, 1867. Serial No. 230,601. (No model.)

To all whom it may concern:

Be it known that I, LOUIS A. SCHMIDT, of Brooklyn, county of Kings, and State of New York, have invented certain new and useful 5 Improvements in Ventilating Head-Supports or Pillows, of which the following is a specification.

This invention relates to a new and improved head support or pillow for use in summer or in countries having a hot climate; and the object of my invention is to provide a head-support or pillow which is so constructed that the air can circulate through the same, thus keeping the head and upper part of the 15 body of the person resting on said support cool and comfortable even in the hottest days.

The invention consists in a folding frame provided with braces, a piece of gauze or netting held on the said frame, the upper part of 20 which netting is horizontal and the lower part inclined, all as will be fully described herein-after, and finally pointed out in the claims.

In the accompanying drawings, Figure 1 is a perspective view of my improved ventilating head-support or pillow, the same being applied to a bed. Fig. 2 is a longitudinal sectional view of the same on the line *x x*, Fig. 3. Fig. 3 is a plan view of the same, showing one side folded, parts being broken out. Fig. 4 is 30 an end view of the same, showing one side folded. Fig. 5 is a detail side and top view of a bolt for holding the gauze or netting.

Similar letters of reference indicate corresponding parts.

35 The two side bars, A, are united by three cross-bars, B B' B''. On the ends of the cross-bars B and B' the blocks C are secured, to which the standards D are pivoted in such a manner that they can fold inward and toward 40 the cross-bars.

On the inner side of each standard a brace, E, is pivoted, which serves to hold the standards in vertical position, the lower end of the brace being adapted to pass into the notch F 45 in the upper surface of the cross-bar. Each standard is provided with a series of apertures, H, through which a bolt, J, can be passed, which bolt is provided at one end with an aperture for receiving a spring-pin, K, and 50 at the other end with two jaws, L, through which a rivet, M, can be passed. The bolt J

is passed through an aperture, H, in each standard D in such a manner that the jaws L are on the inner sides, the bolts being held in place by the spring-pins K. A sheet or piece, 55 N, of strong netting has strips, O, of canvas or like material secured to its sides. One end of said sheet N is fastened securely to the cross-bar B', and the side strips, O, of said netting are held by the rivets M between the jaws L. By 60 swinging up the standards D and bracing them by means of the braces E, the netting is drawn taut and serves as a pillow or head-rest that is thoroughly ventilated, as the air can circulate through the interstices of the netting and 65 under the netting.

The netting can be adjusted by means of the bolts J, and can be held at different heights on the cross-bars B and B'. When not in use, the entire device can be folded very compactly 70 by disengaging the braces E from the notches F, resting them against the standards D, and then folding the standards down upon the cross-bars.

Having thus described my invention, I claim 75 as new and desire to secure by Letters Patent—

1. In a head-rest, the combination of the side bars, A, the cross-bars B B' B'', hinged standards D, the braces E, and the netting N, to secure it to the brace-bar B' at one end, and held 80 at the other end by clips in the standards D, substantially as shown and described.

2. In a head-rest, the combination of the two side bars, united by cross-bars B B' B'', the standards D, hinged on the ends of said 85 cross-bars B B' and provided with apertures H, braces E, hinged to the inner sides of the standards, bolts or clips J, passed through apertures H, projecting jaws on the bolts J, rivets M in the jaws, spring-pins K, passing 90 through apertures in the bolts, and a piece of netting held on the cross-bar and stretched over the cross-bars and standards D, substantially as shown and described.

In testimony that I claim the foregoing as 95 my invention I have signed my name in presence of two subscribing witnesses.

LOUIS A. SCHMIDT.
